DESIGN FOR AN UTRAVIOLET STERILIZER

George E. Glatthar, University Heights, and
Joseph Terr, Cleveland Heights, Ohio, assignors
to The Art Metal Company, Cleveland, Ohio,
a corporation of Ohio

Application May 31, 1945, Serial No. 119,823

Term of patent 14 years

(Cl. D83—1)

To all whom it may concern:

Be it known that we, George E. Glatthar and Joseph Terr, citizens of the United States and residents of University Heights and Cleveland Heights, respectively, in the county of Cuyahoga and State of Ohio, have invented a new, original, and ornamental Design for an Ultraviolet Sterilizer, of which the following is a specification, reference being had to the accompanying drawing, forming a part thereof.

In said drawing, Fig. 1 is a front view of an

ultraviolet sterilizer showing our new design; Fig. 2 is an end view of the sterilizer (the view being illustrative of either end); Fig. 3 is a cross-sectional view of the sterilizer, on the line 3—3 of Fig. 1; and Fig. 4 is a top plan view of the sterilizer.

We claim:

The ornamental design for an ultraviolet sterilizer, substantially as shown.
